UNITED STATES PATENT OFFICE.

GARLAND P. SPRINGFIELD, OF EVANSVILLE, INDIANA, ASSIGNOR OF ONE-HALF TO
RAYMOND C. SMITH, OF VANDERBURG COUNTY, INDIANA.

RAILROAD-CROSSING SAFETY DEVICE.

Application filed August 30, 1926. Serial No. 132,514.

This invention relates to a railroad crossing safety device adapted to be arranged as a barrier to prevent a vehicle from crossing a railroad track when a train is approaching and yet permitting the vehicle to back off of the crossing if trapped thereon.

Despite the provision of safety gates and signals at railroad crossings, many motorists recklessly drive their automobiles on the track even though the signal is flashing or ringing to indicate the approach of a train.

My invention provides means for raising a barrier which will prevent any vehicle, such as an automobile, from passing on to the track when a train is approaching, said barrier being automatically operated by the train regardless of whether the signals are functioning or are out of order.

My invention enables the driver of the vehicle to back off of the crossing if trapped between the barriers, or, if he has time to get off the crossing, to permit him to pass to the other side. However, if the vehicle arrives at the crossing after the barrier has been set, it is impossible for the vehicle to pass on to the crossing although such vehicle may be damaged if the attempt is made.

A practical embodiment of the invention is set forth hereinafter and is shown in the accompanying drawings in which:

Figure 1, is a vertical section, the barriers being raised;

Fig. 2, is a plan view, the barriers being lowered.

Fig. 3, is a detail view of the spring connection for the barrier or gate, the barrier being shown as partially depressed.

On opposite sides of the crossing 3 are located swinging or hinged barriers or gates 4 which, as shown, are in the form of bails of heavy construction which are mounted in bearings 5 so that they may be swung upwardly as shown in Fig. 1 by means herein-after described, or may be arranged horizontally sunk below the crossing 3 as shown in full lines in Fig. 2 or swung backward by a vehicle passing off of the crossing as illustrated in Fig. 1 by dotted lines.

The dotted lines 4^a, Fig. 1 illustrate the adaptability of the barriers or gates 4 to be swung down when they are in raised or safety position if the vehicle is trapped be-

tween them and the driver either desires to back off of the crossing or, finding he has time to pass, decides to drive over the crossing. The arrows "a" indicate this action. On the other hand, the arrows "b" indicate the direction of approach of a vehicle to the crossing and the manner in which the barriers or gates prevent the vehicle running on to the crossing.

The track appears at 6. At suitable distances on either side of the crossing track instruments or electrical contacts 7 are provided by which the train completes the electrical circuits 9 which supply the current for operating the means for raising gates 4.

Any suitable source of current, such as a battery may be used for furnishing the current. Installations used on steam railroads will utilize electrical current from batteries or according to any approved practice whereas installations on electric roads may derive the current from the trolley or third rail. 75 Barriers 4 are operated by electric motors 10 whose shafts carry the pinions 11 which mesh with gears 12 on the vertical shafts 13, the latter being suitably mounted in bearings 14. Slidably mounted on the shafts 13 are 80 collars 15 provided with pins 16. Governor balls 18 are carried by arms 19, which are pivoted to the collars 15 and to the bearings 14. Bell-crank-levers 20 which are suitably mounted at 21 have one arm slotted at 22 to receive the pins 16. The other arms of the bell-crank-levers are slotted at 23 to receive the arms 24 which are connected to the gates or barriers 4. 85

The barriers or gates 4 are pivoted to arms 90 24 and permitted to yield in relation to the arms 24 to assume the positions shown at 4^a when a vehicle backs off of the crossing or passes from the crossing away from it. This arrangement comprises a spring tension 95 means consisting of the pivoted cup 25 and a contractile coil spring 26, the cup being pivoted to the bracket 21, said bracket being cast in a single piece with the arm 24. Normally, the barriers 4 are in the position 100 shown in full lines, Fig. 2, but if a vehicle is trapped between the two barriers 4 after they have been raised by the approach of a train, the driver can advance and depress the barrier 4 which is in front of him, or, he 105 can back off of the crossing and depress that

barrier. The arrows, and dotted lines, Fig. 1, show how the barriers may be depressed outwardly in relation to the railroad track. In Fig. 3, the barrier is shown in partly depressed position, as would be the case when, after it has been raised, it is run over by the vehicle but when it is released, the barrier 4 rises again and assumes the position shown in full lines, Fig. 1.

Consequently, while the barrier may yield in the manner previously set forth, it cannot be depressed when the vehicle attempts to run on to the crossing, if said barrier is in raised position because the barrier is blocked by the bracket 27.

Normally, the weight of the governor balls 18 will cause the collars 15 to slide downwardly, thereby lowering the barriers below the crossing but when a train is approaching, the circuits are completed at 7 and the motors 10 are energized, thereby rapidly turning the shafts 13, causing governor balls 18 to swing upwardly, and raising the barriers.

When the train has passed, the circuits are

broken and the governor balls 18 then drop, throwing the gates or barriers 4 downwardly.

What I claim is:

A safety device for railroad crossings comprising a gate or barrier hinged in the region 30 of the level of the crossing and which is adapted to be arranged in an upright position to form an obstruction at the crossing to bar the passage of a vehicle, or to be lowered away from the track to permit passage from the crossing, means being provided to prevent the gate or barrier from being swung downwardly toward the track when said barrier has been raised, and power means for arranging and maintaining the 40 gate or barrier in raised position consisting of a motor and a centrifugal weight-operated governor by which the barrier is raised and kept in raised position so long as the motor operates, the weights of said governor dropping and automatically lowering the gate or barrier when the motor ceases to operate. 45

In testimony whereof I affix my signature.

GARLAND P. SPRINGFIELD.
